UNITED STATES PATENT OFFICE

2,529,239

POCKET ATOMIZER

Arthur Arbetman, Newark, N. J., assignor to Rodman Trading Corp., Little Neck, N. Y., a corporation of New York

Application January 3, 1948, Serial No. 437

4 Claims. (Cl. 299—88)

1

This invention relates to atomizers for spraying perfume or the like, and more particularly to an improved construction for use in the "Cosmetic Device" shown in my copending application, Serial No. 766,068, filed August 4, 1947, of which the instant application is a continuation-in-part.

The atomizer shown in my said copending application is arranged to be closed by an associated liquid cosmetic holder and to act as a closure for a lipstick applicator. As described in said application, the atomizer includes a liquid compartment formed by angularly intersecting passages drilled in the atomizer casing and closed at the lower end by a plug. An air passage and a pump chamber are drilled in the casing and connected by a cross-passage drilled laterally of the casing and likewise closed at its lateral end by a plug.

The present invention is directed to an improved construction eliminating the more complicated drilling and plugging operations used in the atomizer. In the present construction, four longitudinal passages are drilled in the casing in parallel relation. Three of these passages are substantially equal in diameter, while the fourth is of larger diameter. Two of the smaller diameter passages act as a liquid container and are closed at their outer ends by a filler cap and a liquid nozzle, respectively. The third small diameter passage is an air chamber closed at its outer end by an air nozzle for directing air across the liquid nozzle to aspirate liquid therethrough. The fourth passage is a pumping chamber, acting as a cylinder for a plunger-actuated piston to force air through the air chamber.

A novel feature of the invention is the manner of providing cross connections between the two passages of the liquid container and between the air chamber and the pump chamber. This is accomplished by milling or otherwise cutting shallow slots in the casing material separating the two liquid passages and in that separating the air and pump chambers. A plate is then secured to the lower end of the atomizer and provided with interior circular bosses fitting each of the drilled passages, with connecting bosses between the circular bosses and aligned with the slots. The heights of the connecting bosses are less than the depths of the slots, so that small area cross passages are left respectively connecting the two liquid passages together and the air chamber to the pump chamber.

2

An object of the invention is, therefore, to provide an improved atomizer construction.

Another object is to provide an improved and simplified internal construction for an atomizer.

5 These and other objects, advantages and novel features of the invention will be apparent from the following description and the accompanying drawing.

In the drawings:

10 Figs. 1 and 2 are respectively top plan and elevation views of the atomizer in the closed or inoperative position.

Figs. 3 and 4 are top plan and elevation views, respectively, of the atomizer in the operative position.

15 Figs. 5, 6 and 7 are transverse sectional views on the lines 5—5, 6—6 and 7—7, respectively of Fig. 1.

Fig. 8 is a top plan view of a bottom closure plate for the atomizer.

20 Referring to the drawing, the atomizer, which is generally similar to that shown in my said copending application, includes a casing or body 10 having a shoulder 11. As described in my copending application, the atomizer is closed by a liquid cosmetic applicator having a casing whose lower end fits over shoulder 11. Similarly, a shell fits over casing 10 against shoulder 11 and extends beyond casing 10 to act as a closure for a lipstick applicator. As the associated liquid cosmetic and lipstick applicators are substantially the same as in my copending application, they have been omitted from the drawing to simplify the same and because the present 25 invention is directed to construction improvements in the atomizer.

30 Casing 10 has four passages 15, 20, 25 and 30 drilled longitudinally thereof, with passages 15, 20 and 25 being relatively small in diameter and passage 30 being relatively large in diameter. Passages 15 and 20 combine to form a liquid chamber, and are closed by a filter cap 16 and a liquid nozzle member 21, respectively. The upper end of passage 15 is threaded, to receive cap 16, and ends in an enlarged recess 17 in which a flange 18 on cap 16 seats to seal passage 15. An air inlet is formed by a slot 19 milled in recess 17 and through threads 12.

35 Nozzle member 21 has an enlarged upper end 22 press-fitted in passage or bore 20 and terminating in a conical nozzle 23. A liquid tube 24 extends downwardly from section 22 into passage 20.

40 Passage or bore 25 forms an air chamber, whose upper end is closed by an air nozzle mem-

ber 26. Member 26 includes a reduced boss 27 press fitted in bore 25 and an enlarged nozzle portion 28. An air nozzle 29 projects radially and upwardly from portion 28 toward liquid nozzle 23. A passage 13 in boss 27 and portion 28 connects nozzle 29 to air chamber 25 so that air may be forced over nozzle 23 to aspirate liquid, such as perfume, through nozzle member 21.

Passage 30 acts as a pump chamber to force air through air chamber 25. A bushing or collar 31 is press fitted in the upper end of bore 30 and has a central aperture 32 through which passes a plunger rod 33. Aperture 32 is slightly larger than rod 33 so that air may pass into chamber 30 around rod 33. Rod 33 has a decorative operating head 34 on its upper end, shown as resembling a seashell. Head 34 has a projecting lip 36, with an arcuate edge, for a purpose to be described. The inner end of rod 33 is reduced, as at 37, to receive a washer 38, molded from a suitable plastic material, which is flexible enough to be forced over the inner end of rod 33.

A novel feature of the invention is the manner of providing cross-passages between bores 15 and 20, and bosses 25 and 30. Referring more particularly to Fig. 8, a closure member or plate 40 is provided having circular bosses 45, 50, 55 and 60 respectively of the same diameter and in the same relative locations as passages 15, 20 25 and 30.

To interconnect the respective bores, a cross cut 41 is milled or otherwise formed in the material 42 of casing 10 separating bores 15 and 20. Similarly a cross cut 43 is formed in the material 42 between bores 25 and 30. Corresponding to these cuts, connecting bosses 46, 47 are formed on plate 40 between circular bosses 45, 50 and 55, 60, respectively, but their heights are less than the depths of cuts 41, 43.

To complete the atomizer, a spring 48 is placed in pump chamber 30 against washer 38 and plate 40 is secured to the outer or lower end of casing 10. In such securing, circular bosses 45, 50, 55 and 60 are aligned with bores 15, 20, 25, and 30, respectively. As these latter bosses are less in height than the depth of the cross cuts, small cross-passages are left connecting bores 15, 20 and 25, 30 respectively.

Spring 48 whose lower end seats on boss 60 normally biases rod 33 and washer 38 outwardly. To lock the rod in its inoperative position, head 34 is turned to engage lip 36 beneath head 14 of cap 16, with the arcuate edge of the lip seating against the cylindrical surface of cap 16. To operate the atomizer, head 34 is turned to release lip 36, and rod 33 and washer 38 may then be reciprocated to force air through nozzle 29 and across nozzle 23 to aspirate perfume therethrough.

While a specific embodiment of the invention has been shown and described in detail to illustrate the application of the principles thereof, it will be understood that the invention may be otherwise embodied without departing from such principles.

What is claimed is:

1. In an atomizer, a body having at least one pair of bores extending longitudinally therethrough in transversely spaced relation and each defining a passage, a slot in one end of the body extending between the bores for interconnecting the passages at one end of the latter, and a plate secured to said one end of the body and closing such one end of the passages defined by

the bores, said plate having a boss fitting in the slot but of less height than the depth of the slot whereby to define, with the slot, a small cross passage interconnecting the first-named passages.

2. In an atomizer, a body having first and second pairs of bores extending longitudinally therethrough in transversely spaced relation, said first pair of bores defining a pair of liquid passages and said second pair of bores defining a pair of air passages, a pair of slots in one end of the body each extending between the bores of a different pair, one slot interconnecting one end of the liquid passages and the other slot interconnecting one end of the air passages, a plate secured to said one end of the body and closing such one end of the passages defined by the bores, said plate having a pair of bosses each fitting in a slot but of less height than the depth of the slot whereby to define, with the slots, a small cross passage interconnecting the two liquid passages and a small cross passage interconnecting the two air passages, and the other ends of the air passages and the other end of one liquid

25 passage receiving means cooperable to aspirate liquid from such one liquid passage.

3. In an atomizer, a body having first and second pairs of bores extending longitudinally therethrough in transversely spaced relation, said 30 first pair of bores defining a pair of liquid passages and said second pair of bores defining a pair of air passages, a pair of slots in one end of the body each extending between the bores of a different pair, one slot interconnecting one end 35 of the liquid passages and the other slot interconnecting one end of the air passages, a plate secured to said one end of the body and having, on its inner surface, a first pair of bores each fitting in and closing one end of the air passages, and a pair of cross bosses each fitting a different one of said slots and each interconnecting the bosses of a different one of said pairs of bosses, said cross bosses being of less height than the depth of said slots to form a small cross passage 40 interconnecting the two liquid passages and a small cross passage interconnecting the two air passages, and the other ends of the air passages and the other end of one liquid passage receiving 45 means cooperable to aspirate liquid from such one liquid passage.

4. In an atomizer, a body having first and second pairs of bores extending longitudinally therethrough in transversely spaced relation, said 50 first pair of bores defining a pair of liquid passages and said second pair of bores defining a pair of air passages, a pair of slots in one end of the body each extending between the bores of a different pair, one slot interconnecting one end 55 of the liquid passages and the other slot interconnecting one end of the air passages, a plate secured to said one end of the body and closing such one end of the passages defined by the bores, said plate having a pair of bosses each fitting 60 in a slot but of less height than the depth of the slot whereby to define, with the slots, a small cross passage interconnecting the two liquid passages and a small cross passage interconnecting the two air passages, and the other ends of the 65 air passages and the other end of one liquid passage receiving means cooperable to aspirate liquid from such one liquid passage, the other end of the bore forming the other liquid passage having a slot extending longitudinally of its wall where- 70 by to form, when a closure is secured to the other

end of said other liquid passage, a small air inlet opening thereinto.
